FIG. 3.

Patented Aug. 14, 1928.

Des. 75,997

UNITED STATES PATENT OFFICE.

ALLAN C. AXFORD, OF SAN FRANCISCO, CALIFORNIA.

DESIGN FOR A FIREPLACE GRATE.

Application filed January 11, 1928. Serial No. 24,829. Term of patent 14 years.

To all whom it may concern:

Be it known that I, ALLAN C. AXFORD, a citizen of the United States, residing at 557 Treat Avenue, city and county of San Francisco, State of California, have invented a new, original, and ornamental Design for Fireplace Grates, of which the following is a specification, reference being had to the accompanying drawing, forming part thereof.

Figure 1 is a plan view of the grate,
Figure 2 is an elevation looking from the back of the grate, and

Figure 3 is an end elevation of the grate.
I claim:

The ornamental design for a fireplace grate as shown.

ALLAN C. AXFORD.
